UNITED STATES PATENT OFFICE.

JESSE E. SMITH, OF HOLLYWOOD, CALIFORNIA.

AUXILIARY ORGAN KEYBOARD FOR TUNING.

Application filed July 1, 1921. Serial No. 481,760.

To all whom it may concern:

Be it known that I, JESSE E. SMITH, a citizen of the United States, residing at Hollywood, in the county of Los Angeles and State of California, have invented certain new and useful Improvements in Auxiliary Organ Keyboards for Tuning, of which the following is a specification.

This invention is a circuit closing device, for use in connection with an auxiliary portable keyboard, of the type employed to tune organs.

One of the objects of the invention is to provide simple means for closing an electric circuit, and maintaining it in closed condition, during the period of depression of the auxiliary testing key, with which it is associated. A further object is to provide means for automatically actuating each circuit closer, to open its circuit, when another testing key is actuated. A further object is to provide means whereby a plurality of circuit closers may be simultaneously operated.

The invention will be hereinafter fully set forth and particularly pointed out in the claims.

Referring to the drawings:—

Figure 1 shows a top view or plan of an auxiliary key board, with the cover open, and equipped with the invention. Figure 2 shows a cross-sectional elevation of the same. Figure 3 shows a detailed sectional view along line 3—3 of Figure 1. Figure 4 shows a top view or plan of the inner arrangement of the box containing the mechanism of the auxiliary key board, the key board base being thrown back and inverted. Figure 5 shows a diagrammatical view of the different parts of the auxiliary key board in relation to an electrical organ. Figure 6 shows a top view of two sets of finger bars used for connection with the source of electrical energy by which the organ is operated. Figure 7 shows a back view of part 45 of the finger bars. Figure 8 shows a sectional elevation of the same. Figure 9 shows a diagrammatical view of the wiring of the auxiliary key board in connection with an electrical organ.

In an organ the keys of the stationary key board by which the organ is played are connected with the magnets which control the air supply to the organ pipes, by means of

suitable wires leading from a source of electrical energy. 55

The tuning of the pipes which in a large organ are frequently at a considerable distance from the keyboard involves without the aid of an assistant, a great deal of walking, climbing of ladders and various inconveniences, while even the presence of an assistant means the giving of instructions from a distant point, conversation in a rather loud voice, frequent misunderstandings, loss of time and irritating incidents which tend to 65 impair the efficiency of the tuner, especially as perfect silence is a point almost essential to achieve satisfactory results.

These various annoying details are entirely overcome by the use of an auxiliary keyboard equipped with the circuit-closing elements of the present invention, which allows the operator to produce any desired note or notes, employ any stop or stops while stationed at any part of the organ. 75

The organ keyboard is conventionally represented at K, Figure 5, the organ pipe actuating magnets 2, being shown as provided with wires k—k'. A rail 3 of insulating material is supported in any convenient position, said rail being provided with a number of contact pins 4 corresponding to the number of organ keys, and also provided with a number of contact pins 5 corresponding to the number of organ stops. A wire 6 leads from battery 1 to a terminal bar 7 in a portable auxiliary keyboard-enclosing box 8. Said box 8 contains the auxiliary keyboard which consists of a plurality of suitably mounted keys or buttons 24. Metal contact fingers 10 in the lower part of box 8 are separately connected by insulated wires 11 to an equal number of metal strips or fingers 12 carried by a finger bar 13, and metal strips 14 are similarly connected to fingers 15 attached to a finger bar 16. It will be noted that the fingers 12 contact with the pins 4 and that the fingers 15 contact with the pins 5, the current passing through wires 17 and K' to the magnets and returning through the wires K and 19 to battery 1, thus completing the circuit. By this means the magnets may be energized by a plurality of shunt circuits. It is to be understood that magnets corresponding to the magnets 2 are 100 similarly connected with the organ stops.

Pins 20, equal in number to the number of stops in the organ, are electrically connected to terminal bar 7. When pushed downward the pins 20 contact with metal strips 14, thus completing the stop circuit of the auxiliary keyboard and causing the current to pass through and energize the magnets 21 controlling the stops.

Wire 6 and wires 11 are gathered in cables 22, as shown in Figure 5, of sufficient length to allow the auxiliary keyboard to be carried conveniently to any desired part of the organ.

In practice the operator depresses any particular push button 24, thereby forcing the attached pin 23 downwardly until it becomes engaged with the contiguous metal strips 10 and a recess 25 in the contiguous pivoted spring held contact bar 26. Thus the circuit is closed from contact 7 through contact 37, bar 26, pin 23, strip 10, cable 22, individual wire 11, finger 12, pin 4, wire 17, wires k and k' , the included magnets 2 and wire 19 back to battery 1. The pushing down of another key releases automatically the preceding one, while a number of notes or chords may be sounded by pushing down the required keys simultaneously.

Releasing pin 27, upon being pressed down, engages one of the contact bars 26, which normally lies in its path, see Figure 3. Inasmuch as both bars are connected by link 28 (see Figure 2), both contact bars 26 will be pushed out of contacting position. Thus, the pins 23, are released from their engagement with the metal fingers 10 and bars 26, thus breaking the key circuits and ending the organ notes. In this manner it is possible to hold any number of keys down and play the organ by the auxiliary keyboard in exactly the same manner as by the organ keyboard.

The keyboard may be enclosed within the box 8 of insulation. The box is composed of two members, a lower member 31 and an upper member 32. To the top of one side of the lower member 31 is hinged a keyboard base 33 of insulation, in which the keys 24, 20 and pin 27 are slidably mounted. The upper box member 32 is hinged to the top of the base 33 at one side thereof. The ends and the other side of the member 32 extend down over the ends and other side of the base and rest upon the ends and other side of the lower box member 31, thus enclosing the keyboard within the box. The keys 24 are slidably mounted in openings 34, extending through the base, and metal plates 35 are secured to the bottom of base 33 over the key openings, through which openings extend the key pins 23. Springs 36 are interposed between the plates 35 and the keys 24 which are adapted to force the keys upwardly until the heads of the pins engage the plates 35, whereby the keys are normal-

ly maintained in their upper inactive positions. One of the plates 35 is electrically connected to terminal bar 7 by metal strip 37.

The pins 20 are slidably mounted in the base 33 and extend therethrough and through a metal bar 38 which is electrically connected to plate 35 by metal strip 39. The bars 26 are pivoted to the plates 35 at 40. A spring 41 is connected at its ends to the base 33 and one of the bars 26 which spring normally maintains the bars 26 in their upper position adjacent the contact points of the spring strips 10.

The spring strips 10 and 14 are secured between bars 45 and 46 and the bars 45 are provided with notches 47 to receive the strips to permit the spring contacting movement thereof. Springs 48 are mounted in recesses in the bars 45 which bear against the spring fingers 10 and 14 and assist in maintaining the strips in their contacting position. The box and the keyboard enclosed therein may be readily carried around and placed in any convenient location to be operated by the tuner. In order to operate the keyboard the top member 32 of the box is swung up on its hinges exposing the keyboard so that it may be operated. The keyboard is normally held in operative position within the box by a latch 50. Upon disengaging the latch the base 33 and parts mounted thereon may be swung up on hinges of the base so that access may be had to the parts on the under side of the base and to the lower interior of the box.

The head 23 of any key 24, which has been depressed, is caught in the recess 25 of the contiguous bar 26, and held therein by the contiguous spring contact finger 10, thereby preventing return of the depressed key to its normal position. Just as soon as any other key is depressed far enough for its head 23 to engage the bar 26, said bar is first swung out of engagement with the previously depressed key, whereupon the spring 36 of the last mentioned key will return the latter to its normally inoperative position, thus breaking the organ pipe circuit and arresting the sounding of the note controlled by said circuit. The key which is last depressed is engaged by its spring finger and held in engagement with the bar 26 in a manner already described. In this way the keys may be depressed to sound the respective notes alternately as in playing the organ keyboard. Several keys may be depressed only the proper distance so that all the contact pin heads of said keys may be engaged by the bar shoulders and the spring contacts to close all the circuits of the depressed keys at the same time and to sound all the notes controlled by said circuits contemporaneously. The releasing pin may be depressed into engagement with the 130

contiguous bar 26 to so move said bar as to release any contact pin which may be held between either bar 26 and contiguous contact 10 permitting the push buttons 24 and 5 contact pins 23 to return to inoperative position. In this manner the circuit is broken. Or, the releasing pin 27 may be depressed to engage the contiguous bar 26 and release all the contact pins whereby all of the 10 depressed keys will return to their normal inoperative positions to break all the circuits controlled by said keys and end the notes controlled by said circuits. In this way the keyboard may be operated to play the 15 notes of the organ as they are played by the organ keyboard.

Having thus explained the nature of the invention and described an operative manner of constructing and using the same, 20 although without attempting to set forth all of the forms in which it may be made, or all of the forms of its use, what is claimed is:—

1. The combination with the operating magnets of an organ, of a portable auxiliary 25 keyboard, means for providing temporary shunt circuits for energizing said magnets, there being one shunt circuit for each magnet, and means operated by the keys of said keyboard for closing the respective shunt 30 circuits.

2. The combination with the operating magnets of an organ, of a portable auxiliary keyboard, a rail having pins in circuit with 35 said magnets, means for electrically connecting the said keyboard with said pins, and means operated by the keys of said

key bar for closing the circuits of the respective magnets through said pins.

3. The combination with the operating magnets of an organ, of a portable auxiliary keyboard, a rail, a plurality of pins carried by said rail and in circuit with said magnets, a portable finger bar having contact fingers engaging said pins, and means operated by the keys of said keyboard for 40 closing the circuits to said magnets through 45 said finger bars and contact fingers.

4. The combination with the key and stop-actuating magnets of an organ, of a portable auxiliary keyboard, a rail, a set 50 of pins carried by said rail and in circuit with said key operating magnets, a set of pins also carried by said rail and in circuit with said stop operating magnets, finger bars having contact fingers engaging 55 the respective sets of pins, and means operated by the keys of said keyboard for closing circuits to said magnets through said finger bars and contact fingers.

5. The combination with the operating 60 magnets of an organ, of a portable auxiliary keyboard, means for providing temporary shunt circuits for energizing said magnets, there being one shunt circuit for each 65 magnet, means operated by the keys of said keyboard for closing the respective shunt circuits, means for locking the keys in circuit closing position, and means for releasing said keys at will.

In testimony whereof I affix my signature. 70

JESSE E. SMITH.
